UNITED STATES PATENT OFFICE

FRED L. MACKENZIE, OF BEVERLY, MASSACHUSETTS, ASSIGNOR TO UNITED SHOE MACHINERY CORPORATION, OF PATERSON, NEW JERSEY, A CORPORATION OF NEW JERSEY

FASTENING-INSERTING MACHINE

Application filed September 25, 1930. Serial No. 484,380.

This invention relates to fastening-inserting machines and work-gages therefor and is illustrated herein as embodied in a fastening-inserting machine provided with a work-gage particularly adapted for use in heel-seat nailing in the manufacture of boots and shoes.

In the manufacture of shoes it is customary to fasten the heel-seat portion of the outsole to the shoe upper and insole by driving nails or pegs through the outsole, upper and insole in a line extending from the heel breast line rearwardly around the heel end of the shoe. In attaching the heel-seat portion of the outsole to the heel-seat portion of the other parts of the shoe it is usual to insert the fastening along the straight side of the shoe relatively close to the edge of the shoe, while at the back of the shoe where the outsole is afterwards trimmed off at its greatest angle to conform to the shape of the heel it is desirable that the fastenings be inserted further from the edge of the shoe to prevent contact between the shaving knife and the heel-seat fastenings at this point. In view of this, it is an object of the present invention to provide an improved work-gage adapted for use, for example in heel-seat nailing, by which the location of the edge of the sole of the shoe with respect to the fastening-inserting instrumentalities of the machine is varied according as the fastenings are being inserted in a portion of the sole which has a straight or a curved edge.

With this object in view, and in accordance with a feature of the invention, the illustrated machine is provided with a novel work-gage comprising a pair of freely rotatable rolls arranged to engage the work, one on each side of the line of drive of the fastenings, to guide the work as it is fed past the fastening-inserting instrumentalities of the machine, said rolls being adjustable relatively to each other so that the relation of a shoe the rear part of the counter portion of which is engaged by the rolls may be adjusted, for example, to compensate for the differences in curvature of that part of shoes of different sizes.

It is a further object of the invention to

insure against any marring of the upper leather of the shoe by the gage, as might happen if the rear part of the counter portion of a shoe were caught or jammed between the two rolls of such a gage. With this object in view, the two rolls of the illustrated gage are so interconnected that as one roll is moved rearwardly under pressure applied through the work during the feeding movement thereof the other roll is moved to an equal extent forwardly. Thus variations in the relative positions of the two rolls toward and from the work substantially equalize each other so that the rolls follow, it may be said, the edge of the work without varying substantially the relation of the work piece to the fastening-inserting instrumentalities of the machine.

A further feature of the invention resides in means for adjusting the rolls relatively to each other transversely of the work to determine the point of operation of the fastening-inserting instrumentalities of the machine with respect to the curved portion of the heel-seat of the shoe without affecting the relation of the fastening-inserting instrumentalities to the edge of the work as fastenings are inserted along the straight sides of the heel-seat portion of the shoe.

With the above and other objects and features in view, the invention will now be described in connection with the accompanying drawings and will be pointed out in the claims.

In the drawings, Fig. 1 is a side elevation of the head of a fastening-inserting machine embodying the present invention;

Fig. 2 is a side elevation, on an enlarged scale, showing the work-gage included in Fig. 1 and attached to the presser plate or abutment of the machine;

Fig. 3 is a side elevation of the work-gage shown in Fig. 2 viewed from the opposite side of the machine;

Fig. 4 is a plan view of the work-gage shown in Fig. 2;

Figs. 5, 6 and 7 are detail views of portions of the work-gage shown in Figs. 2 and 3;

Fig. 8 is a diagrammatic view showing the

position of the gage rolls relatively to the edge of the work as fastenings are inserted around the curved portion of the work and, by dotted lines, the relative positions of the 5 rolls as fastenings are inserted along the straight sides of the work; and

Fig. 9 is a diagrammatic view showing two 10 positions of the gage rolls in contact with the edge of the work and the positions of the fastenings with respect to the edge of the work, the spacing of the gage rolls relatively to each other and the spacing of the fastenings relatively to the edge of the work being somewhat exaggerated for purposes of illustration.

While the invention may be embodied in various types of fastening-inserting machines, it is illustrated herein as embodied in a loose nailing machine of the type disclosed 20 in Letters Patent of the United States No. 1,030,775, granted June 25, 1912, on an application filed in the name of George Goddu. The machine is provided with suitable fastening-inserting instrumentalities arranged 25 to insert fastenings in succession in a work-piece held by a work support 20 against a presser plate or work abutment 22 and including an awl 24 by which the work-piece, illustrated as a shoe 25 having a counter portion 27 and an outsole 29, is fed step by step to and past the driver guide and driver of the machine. It will be understood that the awl 24 is constructed and arranged to make fastening-receiving holes in the work-piece presented to the machine as well as to feed the work-piece between the insertion of successive fastenings.

The illustrated machine is provided with 40 novel gage mechanism illustrated as a whole at 26 in Figs. 1, 2 and 3 and in detail in the other figures. The gage mechanism 26 is carried by a bracket 28 pivotally secured to a second bracket 30 slidably connected to the presser plate 22. The upper surface of the 45 bracket 30 is held against the under side of the presser plate 22 by a bolt 32 passing through a slot 34 formed in the bracket 30. The bracket 30 is provided with a slot 36 in longitudinal alinement with the slot 34 and 50 arranged to receive a pin 38 carried by the presser plate 22. The bracket 30 is provided with rack teeth 40 with which mesh the teeth of an adjusting pinion 42 journaled in suitable bearings carried by the presser plate 22. 55 The teeth of the pinion 42 mesh with the teeth of a second pinion 44 formed on the end of a transversely extending shaft 46 journaled in a bearing 49 carried by the presser plate 22. A thin plate 50 secured to the presser plate 60 22 by screws 52 is provided with a series of holes 54 concentric with the fulcrum of the handle 48 and arranged to cooperate with a spring-pressed plunger 56 carried by the handle 48 to maintain the handle 48 and bracket 65 50 in any position of adjustment to which

they may be moved. A pair of guide members 58, 58 pivotally connected to the bracket 28 at 60 are each provided with a way to receive a pair of slide members 62, 62. Carried at the forward end of each of the slide members 62, 62 are a pair of gage members or rolls 70, 70 freely rotatable about parallel axes and mounted for movement in a plane substantially perpendicular to said axes, said rolls being adapted to enter the crease between the outsole and the upper of a shoe to guide the shoe as it is presented to the operating instrumentalities of the machine. The slide members 62, 62 are provided with rack bars 64, 64, the teeth of which mesh with substantially diametrically opposite portions of a pinion 66 fulcrumed upon a stud 68 carried by the bracket 28 and upon which each of the guide members 58, 58 are pivoted. It will be readily seen that the slides 62, 62 are so interconnected that movements of the two slides are always rectilinear or in straight lines and are always equal in extent but opposite in direction.

As illustrated, particularly in Fig. 5, the 70 guide members 58, 58 are mounted for relative adjustment toward and from each other. A hand screw 72 having a right and left hand thread is threaded into a pair of blocks 74, 74 pivotally connected to the guide members 58, 58, so that movement of the screw 72 by means of a nut 76 will vary the spacing of the rolls 70, 70 from each other. This adjustment of the rolls permits the curved portion 75 of the heel-seat to enter between the rolls 70, 70 an amount which will be varied by the operator in accordance with the radius of curvature of the rear of the counter portion of the shoe to be operated on and in accordance with the distance from this curved portion 80 of the work at which the fastenings are to be inserted. In order to hold the rolls 70, 70 in adjusted position a spring-pressed locking pin 78 (shown best in Fig. 7, but also indicated in Fig. 6) carried by a block 85 79 secured to the bracket 28 by means of a screw-and-slot connection is arranged to engage one of a series of teeth formed on a wheel 80 fast to the screw 72. A slot 81 (Fig. 5) formed in the block 79 partially surrounds the wheel 80 and holds the wheel 80 against lateral movement.

In order that the rolls 70, 70 may be held 90 yieldingly against undesired vertical movement the bracket 28 is provided with a rearward extension having a slot 84 formed therein through which passes a screw 82 carried by the bracket 30. The screw 82 is provided at its lower end with an adjusting nut 90 and is surrounded by a pair of springs 86, 88 which bear against washers contacting with the opposite faces of the bracket 28 adjacent to the slot 84. The rolls 70, 70 may be adjusted vertically by movement of the nut 90.

In the operation of the fastening-inserting machine, the awl is moved in a substantially straight line subsequently to its projection into the work to bring the opening thus made 5 in the work in alinement with the driver of the machine. In order that the work may be effectively guided the rolls 70, 70 are mounted and connected in such a way that if one roll is moved rearwardly under pressure applied 10 through the work by means of the awl or by the operator the other roll is moved to an equal extent forwardly. While this floating movement of the rolls is ample to protect the work from being caught or 15 jammed between the two rolls and therefore from being marred in any way, it is not sufficient to have any appreciable effect on the distance between the line of drive and the edge of the work-piece. Thus the fastenings 20 are inserted in a row substantially parallel to the approximately straight portions of the edge of the sole at the sides of the heel-seat, and on a smooth curve at the rear of the heel-seat, the fastenings at the curved 25 portion of the row being further from the edge than those at the straight portions.

The operation of the device will be apparent from an inspection of Figs. 2, 3 and 4 of the drawings. The rolls 70, 70 may be 30 adjusted toward and from the line of feed of the work by means of the operating handle 48 and spaced relatively to each other in the direction of the feed by movement of the hand screw 72. By adjustment of the handle 48 the edge of the work may be brought 35 relatively close to the line of drive. When, however, the curved part at the rear of the counter portion of the shoe enters between the rolls 70, 70, the fastenings will be spaced 40 further from the edge of the sole. Moreover, the spacing of the fastenings from the curved edge of this portion of the sole may be varied by adjustment of the rolls 70, 70 toward and away from each other in the direction of the feed of the work by means of 45 the hand screw 72. Thus the fastenings may be inserted along the curved portion of the heel-seat at the desired distance from the edge of the work without varying the point 50 of operation of the fastening-inserting instrumentalities with respect to the edge of the work as the fastenings are inserted along the straight sides of the heel-seat portion of the shoe.

Having thus described my invention, what I claim as new and desire to secure by Letters Patent of the United States is:

1. A gage for a shoe machine comprising two rolls mounted to rotate freely on spaced 55 parallel axes and movable in a plane substantially perpendicular to said axes, and connections between the two rolls constructed and arranged to control the positions of the two rolls so that rectilinear movement of one roll 60 in a direction away from the work causes

equal rectilinear movement of the other roll in a direction toward the work.

2. A gage for a shoe machine comprising two rolls mounted to rotate freely on spaced 70 parallel axes and freely movable in a plane substantially perpendicular to said axes, and gearing between the two rolls constructed and arranged to control the positions of the two rolls so that as one roll moves in a direction away from the work-piece the other roll moves to an equal extent in a direction toward the work-piece.

3. A gage for a shoe machine having, in combination, a pair of slide members, guides in which the slide members are mounted, 80 connections between the two slides such that movements of the two slides are equal in extent but opposite in direction, and a pair of members at the forward end of each of the slides, formed and arranged to be engaged by a shoe to be operated upon and to guide the shoe as it is presented to the operating instrumentalities of the machine.

4. A gage for a shoe machine having, in combination, a pair of slide members each provided with a rack, guides in which the slide members are mounted for endwise movement, a pinion diametrically opposite portions of which engage the respective racks whereby any movements of the two slides are 90 equal in extent but opposite in direction, and a pair of rolls, one carried at the forward end of each of the slides, formed and arranged to be engaged by a shoe to be operated upon and to guide the shoe as it is presented to the 95 operating instrumentalities of the machine.

5. A gage for a shoe machine having, in combination, a pair of guide members mounted for relative adjustment toward and from each other, a pair of slides, one carried by each of the guide members, a pair of rolls, one mounted at the forward end of each of the slides and arranged for rotation about parallel axes, and connections between the slides so that they can have only equal and 100 substantially opposite movements in the guide members.

6. A gage for a shoe machine having, in combination, a pair of guide members mounted for relative adjustment toward and from each other, a hand screw connected to the guide members and arranged by its rotation to move the forward ends of the guide members toward and from each other, a pair of slides, one carried by each of the guide members, a pair of rolls, one mounted at the forward end of each of the slides and arranged for rotation about parallel axes, and connections between the slides so that they can have 115 only equal and substantially opposite movements in the guide members.

7. A fastening-inserting machine having, in combination, an awl constructed and arranged to make fastening-receiving holes in 120 a work-piece presented to the machine and 125

- to feed the work-piece between the insertion of successive fastenings, and a gage to position the work while it is presented to the machine comprising a pair of work-engaging members spaced somewhat from each other and positioned one on either side of the line of drive, said members being mounted for equal but opposite movement toward and from the work-piece whereby movement of the members under pressure applied through the work-piece does not affect substantially the relation of the work-piece to the fastening-inserting instrumentalities of the machine.
15. 8. A fastening-inserting machine having, in combination, an awl constructed and arranged to make fastening-receiving holes in a work-piece presented to the machine and to feed the work-piece between the insertion of successive fastenings, and a gage to position the work while it is presented to the machine comprising a pair of rolls spaced somewhat from each other and positioned one on either side of the line of drive, said rolls being mounted for equal but opposite movement toward and from the work-piece whereby movement of the rolls under pressure applied through the work-piece is effective to prevent marking of the work by the rolls but does not affect substantially the relation of the work-piece to the fastening-inserting instrumentalities of the machine.
9. A fastening-inserting machine having, in combination, an awl, means for operating said awl to cause it to form a fastening-receiving hole in a work-piece and to feed the work into fastening-receiving position, fastening-inserting means, and a work gage to position the work while it is presented to the machine comprising a pair of work-engaging members initially adjusted to determine the relative positions of the fastenings and the edge of the work as fastenings are inserted in the work, said members being mounted for equal but opposite movement toward and from the work-piece, thereby preventing the work-engaging members from marring the work.
10. A fastening-inserting machine having, in combination, a presser plate, a bracket slidably connected thereto, a pair of guide members pivotally secured to the bracket, a pair of slides carried by the guide members, a pair of rolls, one mounted at the forward end of each of the slides and arranged to engage the edge of a work-piece presented to the machine, connections between said slides whereby the rolls move substantially equal distances in opposite directions, means for adjusting the rolls with respect to the fastening-inserting instrumentalities of the machine to determine the point of operation of the fastening-inserting instrumentalities with respect to the edge of substantially straight-edged portions of the work-piece, and means

for adjusting the rolls relatively to each other to determine the point of operation of the fastening-inserting instrumentalities with respect to the edge of curved portions of the work-piece without affecting the relation of the work-piece to the fastening-inserting instrumentalities as fastenings are inserted along the substantially straight-edged portions of the work.

11. A fastening-inserting machine having, in combination, a presser plate, a bracket slidably connected thereto, a pair of guide members pivotally secured to the bracket, a pair of slides carried by the guide members, a pair of rolls, one mounted at the forward end of each of the slides and arranged to engage the edge of a work-piece presented to the machine, connections between the slides carrying the rolls such that when one slide is moved in one direction the other slide is moved an equal distance in substantially the opposite direction, means for adjusting the rolls with respect to the fastening-inserting instrumentalities of the machine to determine the point of operation of the fastening-inserting instrumentalities with respect to the edge of substantially straight sides of the work-piece, and a hand screw connected to the guide members and arranged by its rotation to move the rolls relatively to each other to determine the point of operation of the fastening-inserting instrumentalities with respect to the edge of curved portions of the work-piece without affecting the relation of the work-piece to the fastening-inserting instrumentalities as fastenings are inserted along the substantially straight sides of the work.

In testimony whereof I have signed my name to this specification.

FRED L. MACKENZIE.
